UNITED STATES PATENT OFFICE.

FRANCES LEONARD MORGAN, OF ROCK MART, GEORGIA.

BEDSTEAD ATTACHMENT.

No. 830,246.

Specification of Letters Patent.

Patented Sept. 4, 1906.

Application filed July 7, 1905. Serial No. 268,632.

To all whom it may concern:

Be it known that I, FRANCES LEONARD MORGAN, a citizen of the United States, residing at Rock Mart, in the county of Polk 5 and State of Georgia, have invented new and useful Improvements in Bedstead Attachments, of which the following is a specification.

This invention relates to bedstead attachments, and has for its objects to produce a comparatively simple inexpensive device of this character which may be readily applied for use, one which in practice will thoroughly protect the lower side of the mattress from 5 dust and the like, and one which in practice will prevent cold air rising beneath the mattress, thus reducing the quantity of bed-covering necessary for warmth.

A further object of the invention is to provide a device of this character in which the retaining members may be readily adjusted for bedsteads of varying widths and one wherein the protecting member or sheet may be readily inserted or removed and will be 5 maintained out of contact with the bedstead.

With these and other objects in view the invention comprises the novel features of construction and combination of parts more fully hereinafter described.

In the accompanying drawings, Figure 1 is a vertical transverse section of a bedstead having an attachment embodying the invention applied thereto, and Fig. 2 is a perspective view of one of the retaining members or 5 wires.

Referring to the drawings, 1 designates a bedstead having side rails 2 provided with inwardly-projecting slat-supporting ribs or flanges 3, these parts being of the usual or any 5 approved construction and material.

In accordance with my invention I provide a plurality of retaining members 4, each consisting of a length of wire or other suitable material designed to extend transversely 5 between the rails 2 and each having at a point between its ends a lap-ring or coil 5, adjustable for varying the length of the member, the latter being provided at its ends with rail-engaging portions or clips 6 in the form of 5 hooks, produced by bending the terminals of the wire into shape. Each of the hooks 6 is spaced from the body of the member 4 and extended inward parallel with the latter to produce a seat or recess 7, the recesses 7 being designed to receive the edges of a protect-

ing member or sheet 8, composed of paper or other suitable material, which will serve as a non-conductor of cold.

In practice the retaining members 4 are applied to the bedstead by engaging the clips 6 or hooks 6 with the slat-receiving flanges 3 of the rails, it being apparent that the length of the respective members may be varied to accord with variations in the width of the bedstead by expanding or contracting the eyes 65 5, thus to insure firm engagement of the clips 6 with the rails. After the retaining members have been properly positioned the protecting-sheet 8 is inserted in place with its longitudinal edges seated in the recesses 7. 70 It is to be noted in this connection that when in place the sheet 8 will lie beneath and wholly cover the lower face of the mattress and will be maintained out of contact with the rails 2 by the intervening portions of the 75 hooks or clips 6. It is apparent that under this construction the protecting-sheet 8 will prevent cold air rising beneath the mattress and will also protect the latter from dust or similar impurities which may be raised while 80 sweeping, it being obvious that inasmuch as the protector serves as a non-conductor of cold a comparatively small quantity of bed-clothing will be necessary in order to obtain 85 adequate warmth.

From the foregoing it is apparent that I produce a simple device admirably adapted for the attainment of the ends in view and one which in practice may be readily applied for use, it being understood that in attaining 90 these ends minor changes in the details herein set forth may be resorted to without departing from the spirit of the invention.

Having thus described the invention, what I claim as new is—

The combination with a bedstead, of a retaining member provided at a point intermediate its ends with a lap ring or coil and having its ends bent to provide hooks and seats, said hooks being designed for engagement 100 with the slat-supporting ribs or flanges of the side rails of the bedstead, and a protecting sheet sustained by said member and entered into said seats.

In testimony whereof I affix my signature 105 in presence of two witnesses.

FRANCES LEONARD MORGAN.
